(57) **CLAIM**

I claim the ornamental design for a frame with seat and head support for infant, as shown and described.

DESCRIPTION

FIG. 1 is a front perspective view of the frame with seat and head support for infant, showing my new design in full lines; FIG. 2 is a rear perspective view of the frame with seat and head support for infant, as shown and described.

FIG. 3 is a front view of the frame with seat and head support for infant in full lines;

FIG. 4 is a rear view of the frame with seat and head support for infant in full lines;

FIG. 5 is a left side view of the frame with seat and head support for infant in full lines;

FIG. 6 is a right side view of the frame with seat and head support for infant in full lines; and,

FIG. 7 is a top view of the frame with seat and head support for infant in full lines.

The broken line showing of portions of the frame with seat, head support and kick pad for infant is included for the purpose of illustrating environmental structure and forms no part of the claimed design.
